Inventor.

UNITED STATES PATENT OFFICE.

ANDREW C. PORTER, OF BATESVILLE, MISSISSIPPI.

COTTON-GIN FEEDER.

SPECIFICATION forming part of Letters Patent No. 261,760, dated July 25, 1882.

Application filed May 13, 1882. (No model.)

To all whom it may concern:

Be it known that I, ANDREW C. PORTER, a citizen of the United States of America, residing at Batesville, in the county of Panola 5 and State of Mississippi, have invented certain new and useful Improvements in Cotton-Gin Feeders; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to a mechanical movement or a combination of mechanical elements combined and arranged for the purpose of operating feed mechanism in machinery in general, and especially in cotton-gin feeders; 20 and the invention consists in the features hereinafter described, and specifically set forth in the claims.

Figure 1 is a side elevation of the mechanical elements arranged in relative and operative position. Figs. 2 and 3 are details.

A represents the apron located in the hopper B relative to the spike-cylinder C, which feeds the cotton to the gin, these portions being of the usual construction and operation 30 and not requiring description further than that the ratchet H is operated by suitable connection with the shaft C' of the cylinder C. In this instance the means employed to communicate power from the shaft of the cylinder to the ratchet consists of the bell-crank lever D D', pivoted upon the stud d, secured to the side of the hopper. At the same pivot is attached loosely an arm, d'', and this arm is connected to the upper arm, D', of the bell-crank by a bolt, E, provided with a thumb-nut, e, both arms being perforated for the passage of the bolt, and a coiled spring, e', being located between the arms, so that it tends to spread the arms, while the thumb-nut tends 40 or serves to draw the arms toward each other. Upon the shaft of the cylinder C is an eccentric, c, upon the opposite sides of the periphery of which the arms d'' and D' ride. To the lower extremity of the bell-crank is attached 45 a ratchet-lever, F, by means of a thumb-screw,

f. This lever is adapted to straddle the ratchet and take into the teeth thereof as an ordinary pawl.

G is a second pawl, which operates to prevent the backward motion of the ratchet.

The ratchet H is secured to one of the shafts H' of the apron A, as usual.

In Fig. 1, I have shown in dotted lines a slotted concentric disk, I, provided with a pawl, J, adjustable in the slot of the disk, which is 60 placed upon the shaft of the cylinder C, outside of the eccentric c and arms D' d'.

This being the construction, the operation is as follows: It will be seen by using the thumb-nut f that the ratchet-lever F may be 65 elevated from the ratchet and secured in an elevated position, so that the cylinder C may continue its rotation and the apron remain at rest. It will also be seen that by tightly binding the arm d' and the upper arm of the bell-crank they are made to tightly embrace the eccentric, and at each rotation thereof the lower end of the bell-crank is caused to oscillate about the pivot d and carry the ratchet-lever F over a certain number of teeth in the 70 ratchet and rotate it in the return movement of the lever F. If the arms are loosened upon the eccentric, so that they touch during only a portion of its entire rotation, the stroke of the lower end of the bell-crank will be in length 75 proportioned to the extent of the periphery of the eccentric, which comes in contact with them during each rotation thereof. By this means the movement of the feed-apron, which is of course intermittent, is regular in extent. 80

If desired, as the eccentric operates positively only in a portion of its rotation to cause a forward movement of the apron through the medium of the ratchet-lever F, that portion of its rotation in which it does not operate may 85 be utilized in moving the apron by means of the slotted disk I and pawl J. In this case of course the pawl J would be curved inwardly toward the case of the hopper to bring its operative end upon the periphery of the 90 ratchet.

Having described my invention and its operation, what I claim, and desire to secure by Letters Patent, is—

1. The combination of the feed-cylinder shaft 100

C', apron-shaft H', the ratchet H, ratchet-lever F, bell-crank D D', arm d', bolt and nut E e, spring e', and eccentric e, substantially as shown and described.

5 2. The combination, with the feed-cylinder C and ratchet H, of the bell-crank D D', arm d', eccentric C, ratchet-lever F, disk I, and ratchet J, substantially as shown and described.

In testimony whereof I affix my signature in presence of two witnesses.

ANDREW C. PORTER.
